CLAIM

The ornamental design for a display screen with animated graphical user interface, as shown and described.

DESCRIPTION

This invention was made with U.S. Government support under Agreement No. W912CG20C0013, awarded by Defense Advanced Research Projects Agency. The Government has certain rights in the invention.

FIG. 1 is a front view of a first image of a first embodiment of a display screen with animated graphical user interface embodying the new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof;

FIG. 11 is a front view of an eleventh image thereof; and

FIG. 12 is a front view of a twelfth image thereof.

FIG. 12 is a front view of a first image of a second embodiment of a display screen with animated graphical user interface embodying the new design;

FIG. 11 is a front view of a second image thereof;

FIG. 10 is a front view of a third image thereof;

FIG. 9 is a front view of a fourth image thereof;

FIG. 8 is a front view of a fifth image thereof;

FIG. 7 is a front view of a sixth image thereof;

FIG. 6 is a front view of a seventh image thereof;

FIG. 5 is a front view of an eighth image thereof;

(Continued)

FIG. 4 is a front view of a ninth image thereof; FIG. 3 is a front view of a tenth image thereof; FIG. 2 is a front view of an eleventh image thereof; and, FIG. 1 is a front view of a twelfth image thereof. The broken line showing of a display screen with graphical user interface is included for the purpose of showing portions of the article which form no part of the claim. The appearance of the transitional image of a first embodiment of the claimed design sequentially transitions between the images shown in FIGS. 1-12. The appearance of the transitional image of a second embodiment of the claimed design sequentially transitions between the images shown in FIGS. 12-1. The process or period in which one image transitions to another image forms no part of the claimed design.
